UNITED STATES PATENT OFFICE

2,302,456

ROOM HEATER

Henry J. De N. McCollum, Chicago, Ill.

Original application June 10, 1939, Serial No. 278,421. Divided and this application January 4, 1941, Serial No. 373,093

8 Claims. (Cl. 126—110)

My invention relates generally to room heaters of the type commonly known as unit heaters, and more particularly to improved electrical circuits and apparatus for controlling the operation of room heaters having a self-contained internal combustion heat generator.

This application is a division of my copending application Serial No. 278,421, filed June 10, 1939.

In general, the heater comprises a combustion chamber, a radiator receiving the products of combustion therefrom, a blower, or its equivalent, to move a combustible mixture of vaporized liquid or gaseous fuel and air and the products of combustion thereof through the combustion chamber and radiator, an igniter to ignite the combustible mixture, and a fan to circulate the air to be heated through the radiator in intimate heat exchange relationship therewith.

It is an object of my invention to provide an improved room heater which may be easily started, which will continue in effective operation without attention, and which has a novel automatic electrical control circuit.

A further object of my invention is to provide an internal combustion heater with a novel control and safety mechanism which automatically energizes the igniter, starts the movement of combustible mixture through the combustion chamber, starts the circulation of air through the radiator and, after combustion has been established turns off the igniter.

A further object of my invention is to provide an internal combustion heater with a novel electrical control circuit which reenergizes the igniter if the flame becomes extinguished, and stops the blower and the air circulating fan if the combustible mixture is not ignited within a reasonable time, or the flame has been extinguished for a substantial time.

A further object is to provide an improved room heater which is dependable, safe, economical and effective in use, requiring a minimum amount of attention to operate, and is economical to manufacture.

Other objects will appear from the following description, reference being had to the accompanying drawings, in which:

Fig. 1 is a front elevation of the heater and a blower for use in conjunction therewith, with the heater casing, combustion chamber and a portion of the radiator shown in vertical section;

Fig. 2 is a diagrammatic representation of the 55 design 116 which is placed in the room to be heat-

heater and an improved electrical circuit for use therewith;

Fig. 3 is a diagrammatic representation similar to Fig. 2, but showing an alternative arrangement.

Referring to Fig. 1, combustible mixture is supplied to the heater, denoted generally by the numeral 10, from a fuel and air mixing chamber 12. This mixing chamber is provided with a 10 Venturi throat 14, a gas inlet metering orifice 16 and air inlet openings 18, which are protected by a shield 20. Gas and air are drawn into this chamber and properly mixed to form a combustible mixture which passes through a tube 22 15 into the combustion chamber 24, and is there ignited either by the burning gases within the chamber or by an igniter 26. If it is desired to use a liquid fuel, a simple carburetor is provided with its outlet connected to the fuel supply line. 20 Although the igniter may take several forms, I prefer to use a heating coil of resistance wire, such as nichrome wire, which is electrically heated to a point above the flash temperature of the fuel used. 25 From the combustion chamber 24 the hot products of combustion pass upwardly through a radiator 28 composed preferably of finned copper tubes and into a header 30. From here the gases are conveyed outside the building through 30 an exhaust pipe 32. To promote this flow through the combustion chamber and radiator, a motor driven centrifugal blower 34 is interposed in the exhaust pipe and maintains the whole system below atmospheric pressure. The 35 radiator 28 is thus heated to a high temperature, and this heat is dissipated into the room by a fan 36 driven by an electric motor 38.

A room heater, as described generally above, is very efficient in its operation, and a small installation will heat a comparatively large room.

Because the entire heat producing portion of the system is sealed and operates below atmospheric pressure, carbon monoxide and other noxious gases cannot leak from the heater. If 45 a leak should develop at any point in the apparatus, air from the room will flow into the heater, and if this leak should be sufficient to extinguish the fire, the fuel will be shut off in a manner to be pointed out later.

50 In the electrical control mechanism shown in Fig. 2, a primary circuit comprises a main line switch 114 which may be used to shut off the heater for extended periods, a thermostatically controlled mercury tilt switch of conventional design 116 which is placed in the room to be heat-

ed in a position remote from the heater and serves to start and stop the heater whenever necessary to maintain the room temperature substantially constant, and the primary 118 of a transformer 120. The transformer is designed to give approximately seven volts in its secondary 122, inasmuch as the secondary circuit includes open contact switch which may more safely be utilized at low voltages.

The automatic electrical control circuit depends for its operation upon two similar thermally responsive switches, one 124 mounted upon the combustion chamber housing and the other 124' secured to the igniter housing. Since these two switches are similar, a description of one will suffice as a description of both.

The switch 124 comprises a top switch blade 128, a bottom blade 130 and a middle blade 132. Each of these blades is insulated from the others by means of insulating strips or blocks 134 and the whole is bound together by screws or rivets extending through insulating tubes (not shown) in a manner well known. The top and bottom blades 128 and 130, respectively, are resilient, while the middle blade 132 comprises a temperature responsive bimetal strip so arranged that its outward end flexes downwardly toward strip 130 as its temperature rises. Each of these strips is provided with one or more contact points at its outward end arranged as follows: a contact point 136 on the lower surface of the upper strip 128, a point 138 normally in contact with point 136 and supported upon a bracket 140 secured to and in electrical contact with the outward end of strip 130, a point 142 on the lower surface of the bimetal strip 132, and a point 144 on strip 130 adapted to cooperate with point 142, but normally separated therefrom at room temperatures or somewhat thereabove.

The similar elements of similar switch 124' are, as follows: top blade 128', lower blade 130', bimetal blade 132', insulating spacers 134', top blade contact 136', offset contact 138', offset contact supporting bracket 140', bimetal blade contact 142' and lower blade contact 144'.

The temperature responsive switch 124 is mounted upon the combustion chamber housing by means of a metal bracket 148, which serves to conduct heat from the housing to the bimetal blade 132. The switch 124' is similarly secured in heat conducting relation to the igniter housing so that when the igniter 26 is energized it will heat the bimetal blade 132' and deflect its outward end downwardly.

In the circuit, as shown in Fig. 2, one end of the transformer secondary 120 is grounded while the other end is electrically connected by a conductor 150 to switch blade 130. This conductor 150 also has a branch 152 leading to switch blade 128'. The top switch blade 128 has a conductor 154 secured thereto leading to the igniter 26, the other side of which is grounded. A conductor 156 connects switch blades 132 and 130', while blade 132' is grounded through the motor of the fan 38 by conductor 158, and through the motor of the blower 34 by means of a branch 160 of the conductor 158.

In operation, the main switch 114 is closed to put the heater in condition to operate. When the thermostat switch 116 closes, the transformer primary 118 is energized, thereby producing a current in the secondary 122, conductor 150, switch blade 130, contact bracket 140, contacts 138 and 136, blade 128, line 154 and igniter 26. As the igniter temperature increases, the bimetal

blade 132' is heated and deflected until contact 142' touches contact 144', thus completing a circuit through the transformer secondary 122, line 150 and branch 152, blade 128', contacts 136' and 138', bracket 140', contacts 144' and 142', blade 132' and thence to ground through lines 158 and fan 38, and through branch 160 and blower 34. This energizes the blower 34 which draws a fuel and air mixture through the system, and the fan 38 which blows air over the radiator tubes and fins.

As soon as the fuel and air mixture starts to flow through the system, it is ignited by the igniter 26. The heat thus generated by the combustion raises the temperature of the bimetal strip 132 and deflects it downwardly until contacts 142 and 144 touch. The closing of contacts 142 and 144 completes an alternative circuit to the fan 38 and blower 34 through conductor 150, blade 130, contacts 144 and 142, bimetal strip 132, line 156, blade 130', contacts 142' and 144', bimetal blade 132' and lines 158 and 160. On slight additional heating, the additional deflection of bimetal strip 132 urges blade 130 downwardly, thus separating contacts 136 and 138, and deenergizing the igniter 26. Additional heating of bimetal blade 132' similarly separates contacts 136' and 138'.

Though switch 124 may be so adjusted that contact points 136 and 138 separate very soon after contact is made between points 142 and 144, the similar switch 124' should be adjusted so that considerable deflection of blade 130' is necessary before points 136' and 138' separate. This is done so that the bimetal blade 132 will have time to heat and complete one alternate circuit to the fan and blower by closing contacts 142 and 144 before the other alternate fan and blower circuit is opened by separating points 136' and 138'. This delay in the separation of points 136' and 138' may be accomplished by making blade 128' with a slight downward flexure, so that because of its resiliency it will follow blade 130' downwardly for a short distance before separating therefrom.

With the heater operating as outlined above, should the fire become extinguished for any reason, the bimetal blade 132 will cool and allow the igniter to become re-energized to ignite the fuel. If the fire does not become rekindled, then continued cooling of bimetal strip 132 separates contacts 142 and 144 and deenergizes the fan and blower motors, thereby shutting off the heater system with the exception of the igniter circuit.

When the system is first started and in succession the igniter is energized and later the fan and blower are started, if the fire should fail to start within a reasonable time, continued heating of bimetal strip 132' by the igniter 26 will open contacts 136' and 138', thereby shutting off the fan and blower. This occurs because the lack of heat in the combustion chamber has resulted in the alternate motor circuit not being completed, inasmuch as points 142 and 144 remain separated at room temperatures.

The alternative circuit shown in Fig. 3 has a temperature responsive switch 162 which is similar to switch 124', excepting that it is provided with an electric heater 164 for its bimetal blade 166. This heater is placed in parallel with the igniter and is energized at the same time as the igniter. The switch 162, therefore, serves the same purpose as switch 124' and may be used in its place in the control circuit shown in Fig. 3, if desired.

Its advantage is that it heats the bimetal blade more quickly and, therefore, energizes the fan and blower sooner than the switch 124', which cannot act until the igniter housing becomes heated, and this heat is conducted to the bimetal blade 132'.

The other elements of switch 162 are an upper blade 168, lower blade 170, upper blade contact 172, lower blade contact 174, lower blade offset bracket 176, offset contact 178, and bimetal blade contact 180. These elements are similar to the comparable elements of switch 124' and, therefore, need no further description here.

A second temperature responsive switch 182 may replace switch 124, and, like switch 124, is in heat conducting relation with the combustion chamber housing. This switch has an upper blade 184, a lower blade 186, an intermediate bimetal blade 188, and insulating spacers 190, all similar to comparable elements of switch 124. The contact points are differently arranged, however, and are as follows: The upper blade 184 is provided with a contact 192 on its lower surface, which at room temperature normally touches a contact 194 on the upper surface of the bimetal blade 188. On the lower surface of blade 188 a contact 196 secured thereto co-operates with, but at room temperature does not touch, a fourth contact 198 secured to the upper surface of blade 186.

The other elements in the circuit are a fan 200, a blower 202, an igniter 204, and a transformer secondary 206, all similar to comparable elements in Fig. 2.

In this circuit, energization of the transformer secondary 206 produces a current flow through conductor 208, bimetal blade 188, contacts 194 and 192, blade 184, conductor 210, igniter 204, and switch heater 164. This energization of the igniter 204 and heater 164 conditions the igniter to ignite the fuel and causes a downward deflection of switch blade 166, thereby completing a circuit to the fan 200 and blower 202 through transformer secondary 206, conductor 208, and a branch 212 thereof, switch blade 168, contacts 172 and 178, contact bracket 176, blade 170, contacts 174 and 180, blade 166 and conductor 214, which is connected to the fan 200 and blower 202 in parallel. This conductor 214 is also connected to switch blade 186 so that after combustion starts and the bimetal blade 188 becomes warmed, its downward deflection will close contacts 196 and 198 and provide an alternate circuit to the fan and blower to provide energization of these units after contacts 172 and 178 have become separated by continued heating of the bimetal strip 166. This alternate circuit consists of the transformer secondary 206, conductor 208, blade 188, contacts 196 and 198, blade 186, and conductor 214, which, as has been explained, is connected to the fan 200 and blower 202.

As the bimetal blade 188 is heated and deflects to complete the alternative fan and blower circuit mentioned above, it separates the contact points 192 and 194 and deenergizes the igniter 204 and bimetal blade heater 164.

It will be appreciated that the circuit of Fig. 3 operates to accomplish the same control effects as the circuit of Fig. 2, and that, if desired, the temperature responsive switch 162 in Fig. 3 may be replaced by a switch heated by the igniter, as is switch 124' of Fig. 2.

From the above description of my heater, it is seen that by closing a single electrical contact, 75 ply, an igniter circuit for supplying current

the operation of the heater is initiated and that it will continue to operate automatically under full control. If, for some reason, the fuel supply should fail, the fan and blower will be shut off. If the fire should become extinguished, the igniter will be re-energized to start combustion again and if within a reasonable time combustion does not start, the fan and blower will be deenergized and the fuel supply shut off.

10 The heater and electrically controlled circuit herein described may be used in connection with the automatic control valve arrangement which shuts off the fuel supply to the heater when the fan is not in operation, and which is described in my aforementioned co-pending application Serial No. 278,421. If this automatic control valve is used, fuel will not be supplied to the combustion chamber until the igniter has reached a temperature high enough to ignite the fuel and the fan has started. If the fan motor should stop, the fuel supply will be discontinued and dangerous overheating of the heater prevented.

15 While I have shown and described a particular embodiment of my invention, it will be readily apparent to those skilled in the art that numerous variations may be made therefrom without departing from the basic principles of the construction disclosed. I, therefore, desire to include in the following claims all such modifications and 20 variations as will be readily apparent to those skilled in the art, and by which substantially the results of my invention may be attained in substantially the same way.

25 I claim:

30 1. In an electrically controlled internal combustion heater having a fuel supply, a combustion chamber, an electrically heated igniter therein, and a radiator receiving the products of combustion therefrom, the combination comprising a source of current supply, a manually operable switch for connecting and disconnecting said source of current supply, an electrically operated fan for circulating air past said radiator, an electrically operated blower for removing the products of combustion therefrom, an igniter circuit for supplying current to said igniter from said source, two alternate circuits for supplying current from said source to said fan and blower, a thermostatic switch in the first of said alternate 35 circuits to close said circuit and supply current to said fan and blower upon the heating of said igniter, and to open said first circuit upon continued heating of said igniter, and a second thermostatic switch responsive to the temperature of said combustion chamber to close the second of said alternate circuits to supply current to said fan and blower and to open said igniter circuit and discontinue the heating of said igniter upon the burning of fuel in said combustion 40 chamber, said thermostatic switches being so adjusted that the second of said alternate circuits is closed before the first of said circuits is opened.

45 2. In an electrically controlled internal combustion heater having a fuel supply, a combustion chamber and a radiator, the combination of a source of current supply, a manually operable switch for connecting and disconnecting said source of current supply, an electrically operated fan for circulating air past said radiator, an electrically operated blower for removing the products of combustion therefrom, two alternate electrical circuits for supplying current to said fan and blower from said source of 50 supply, an igniter circuit for supplying current to said fan and blower upon the heating of said igniter, and to open said igniter circuit and discontinue the heating of said igniter upon the burning of fuel in said combustion chamber, said thermostatic switches being so adjusted that the second of said alternate circuits is closed before the first of said circuits is opened.

55 3. In an electrically controlled internal combustion heater having a fuel supply, a combustion chamber and a radiator, the combination of a source of current supply, a manually operable switch for connecting and disconnecting said source of current supply, an electrically operated fan for circulating air past said radiator, an electrically operated blower for removing the products of combustion therefrom, two alternate electrical circuits for supplying current to said fan and blower from said source of 60 supply, an igniter circuit for supplying current to said fan and blower upon the heating of said igniter, and to open said igniter circuit and discontinue the heating of said igniter upon the burning of fuel in said combustion chamber, said thermostatic switches being so adjusted that the second of said alternate circuits is closed before the first of said circuits is opened.

to said igniter from said source of supply, a bimetallic thermostatic switch responsive to the temperature of said igniter to open said circuit at room temperatures, to close said circuit upon the moderate heating of said igniter, and to open said circuit upon the further heating of said igniter, a second bimetallic thermostatic switch responsive to the temperature of said combustion chamber to close the second of said alternate circuits upon the burning of fuel in said heater, and means to open said igniter circuit upon said burning of fuel, said bimetallic switches being adjusted to close said second alternate circuit before opening said first circuit.

3. In an electrically operated internal combustion heater having a fuel supply, a combustion chamber, and a radiator for receiving the products of combustion therefrom, the combination of a source of current supply, a manually operable switch for connecting and disconnecting said source of supply, an electrically heated igniter in said combustion chamber, an igniter circuit for supplying current to said igniter from said source of supply, an electrically operated fan for circulating air past said radiator, an electrically operated blower for removing the products of combustion therefrom, two alternate circuits for energizing said fan and blower from said source of supply, a thermostatic switch in the first of said alternate circuits responsive to the temperature of an electric switch heater to close said circuit and energize said fan and blower upon the heating of said igniter and to open said first circuit upon the continued heating of said switch by the heater, an electric switch heater in said igniter circuit to heat said thermostatic switch when current is passed through said igniter, and a second thermostatic switch responsive to the temperature of said heater to close the second of said alternate circuits upon the burning of fuel in said combustion chamber, said thermostatic switches being adjusted to provide a continuous supply of current to said fan and blower during the time that combustion occurs in said combustion chamber.

4. In an electrically controlled internal combustion heater having a fuel supply, a combustion chamber, a radiator, a source of current supply, and a manually operable switch to connect and disconnect said source of current supply, the combination comprising an electrically heated igniter in said combustion chamber, an electrically operated fan for circulating air past said radiator, an electrically operated blower to cause the circulation of products of combustion therethrough, an electrical circuit connected to said source of supply for energizing said fan and blower, a thermostatic switch in said circuit, open at room temperatures and operable upon the heating of said igniter to close said circuit and energize said fan and blower, and upon further heating to open said circuit, a second circuit connected to said source of supply, and a thermostatic switch in said second circuit and responsive to the temperature of said heater to energize said fan and blower upon the burning of fuel in said combustion chamber, said thermostatic switches being adjusted to provide a continuous supply of current to said fan and blower during the combustion of fuel in said heater.

5. In an electrically controlled internal combustion heater having a fuel supply, a combustion chamber, and a radiator receiving the products of combustion therefrom, the combination comprising a source of electric current supply, 75

a manually operable switch for connecting and disconnecting said source of current supply, an igniter, an electrically operated fan for circulating air past said radiator, an electrically operated blower for removing the products of combustion therefrom, two alternate electric circuits for energizing said fan and blower, a thermostatic switch in the first of said circuits responsive to the temperature of said igniter to open said circuit at room temperatures, to close said circuit upon moderate heating of said igniter, and to open said circuit upon continued heating of said igniter, a second thermostatic switch responsive to the temperature of said heater in the second of said alternate circuits to energize said fan and blower upon the burning of fuel in said combustion chamber, said thermostatic switches being adjusted to supply current continuously to said fan and blower when combustion occurs in said heater.

6. In an electrically controlled internal combustion heater having a fuel supply, a combustion chamber, and a radiator receiving the products of combustion therefrom, the combination of a source of electric current supply, a manually operable switch for connecting and disconnecting said source of supply, an electrically heated igniter in said combustion chamber, an igniter circuit for supplying current to said igniter from said source of supply, an electric switch heater in said igniter circuit, an electrically energized motor circuit for operating said heater, two alternate circuits for energizing said motor circuit from said source of supply, a thermostatic switch in the first of said alternate circuits responsive to the temperature of said electric switch heater to open said circuit at room temperatures, to close said circuit upon moderate heating of said igniter, and to open said circuit upon continued heating of said igniter, and a second thermostatic switch responsive to the temperature of said heater in the second of said alternate circuits, to open said second circuit at room temperatures, to close said second circuit upon a rise in heater temperature caused by combustion of fuel in said combustion chamber, to open said igniter circuit when said combustion has been established, and to close said igniter circuit at temperatures below those produced by combustion, said thermostatic switches being adjusted to provide an uninterrupted supply of current to said fan and blower during the time that combustion occurs in said combustion chamber.

7. In an electrically controlled internal combustion heater having a fuel supply, a combustion chamber and a radiator receiving the products of combustion therefrom, the combination comprising a source of electric current supply, a manually operable switch for connecting and disconnecting said source of supply, an electrically heated igniter in said combustion chamber, an igniter circuit for supplying current to said igniter from said source of supply, an electrically energized motor circuit for operating said heater, two alternate circuits for energizing said motor circuit from said source of supply, a thermostatic switch in the first of said alternate circuits, open at room temperatures and operative as said igniter is heated to close said first circuit and energize said motor circuit, and upon further heating of said igniter to open said circuit, and a thermostatic switch in the second of said alternate circuits, responsive to the temperature of said heater to close said second circuit and energize said motor circuit when combustion is

established in said combustion chamber, said thermostatic switches being adjusted to provide a continuous supply of current to said motor circuit during the combustion of fuel in said heater.

8. In an electrically operated internal combustion heater having a fuel supply, a combustion chamber and a radiator receiving the products of combustion therefrom, the combination comprising a source of electric current supply, a manually operable switch for connecting and disconnecting said source of supply, an electrically energized motor circuit for operating said heater, an electrically heated igniter in said combustion chamber, an igniter circuit for supplying current to said igniter, a first circuit to energize said motor circuit from said source of supply, a thermostatic switch in said first circuit, open at room

temperatures and operative as said igniter is heated to close said first circuit and energize said motor circuit, and upon further heating of said igniter to open said circuit, a second circuit for energizing said igniter and said motor circuit from said source of supply and a thermostatic switch in said second circuit responsive to the temperature of said heater, and operative at room temperatures to energize said igniter circuit and upon a rise in temperature caused by the burning of fuel in said heater to discontinue the energization of said igniter circuit and to energize said motor circuit, said thermostatic switches being adjusted to provide a continuous supply of current to said motor circuit during operation of said heater.

HENRY J. DE N. McCOLLUM.
